(57) **CLAIM**

The ornamental design for a “round handle for a push pin or magnet,” as shown and described.

DESCRIPTION

FIG. 1 is a top perspective view of a “round handle for a push pin or magnet” showing my new design;

FIG. 2 is an elevational view thereof;

FIG. 3 is a top plan view thereof;

FIG. 4 is a bottom plan view thereof; and,

FIG. 5 is a bottom perspective view thereof.

The material shown in phantom in FIGS. 1, 2, 4 and 5 is for environment only and does not form a part of the design.
